INVENTOR:

John A. Josselyn

UNITED STATES PATENT OFFICE.

JOHN A. JOSSELYN, OF BROOKFIELD, MASSACHUSETTS.

MACHINE FOR SPLITTING SCRAP-LEATHER.

SPECIFICATION forming part of Letters Patent No. 381,075, dated April 10, 1888.

Application filed October 11, 1886. Serial No. 215,841. (No model.)

To all whom it may concern:

Be it known that I, JOHN A. JOSSELYN, of the town of Brookfield, county of Worcester, and Commonwealth of Massachusetts, have invented certain new and useful Improvements in Scrap-Leather Splitting Machines; and I do hereby declare the following to be a full, clear, and exact description of the same, reference being had to the accompanying drawings and letters of reference marked thereon, forming a part of this specification, and in which—

Figure 1 represents so much of a scrap-leather-splitting machine with my improvements applied thereto as is necessary to illustrate my said invention. Fig. 2 represents a section on line *a a*, Fig. 1, looking in the direction indicated by the arrow, same figure; and Fig. 3 represents a section indicated by line *b*, Fig. 1, the feeding-rolls not being shown.

To enable those skilled in the art to which my invention belongs to make and use the same, I will proceed to describe the invention more in detail.

In the drawings, A is the bed; B, the splitting-knife; C, the edging-knife; D, the leather-opener; E, the knife support; F F, the vertical fluted feed-rolls; G G, burr feed-rolls; but as all of these parts are fully shown and described in Letters Patent granted to me April 13, 1886, a further detailed description is unnecessary in the present specification.

In a scrap-leather-splitting machine it is necessary to have a seam-guide, H, to extend at least from the edging-knife C beyond the action of the second pair, J J', of scrap-leather feed-rolls I I' J J'. The feed-rolls I I' and J J' are supported in suitable bearings, the construction of which is well known and common in this class of machinery, as illustrated in the patents to George L. Tyler, March 5, 1881, No. 242,079, February 7, 1882, No. 253,449, and June 2, 1885, No. 319,357. A further description of the same is therefore unnecessary in this specification, and only sections of the journals K K' and L L' of the feed-wheels I I' and J J' are shown. The journal K of the feed-roll I does not extend beyond the outer end of the feed-rolls, or the end of the feed-roll next to the seam-guide H.

A piece of scrap-leather, M, is shown passing between the feed-rolls I I' J J' to be split

by the knife B, its outer edge, N, being trimmed or evened by the edging-knife C, the uneven edge O being cut off. (See Fig. 1.)

As the splitting-knife is arranged in this class of machines to leave a narrow uncut portion to form a hinge or seam between the split portions when they are flattened out, as fully described in my said patent of April 13, 1886, it is desirable to have the scrap pieces pushed against the seam-guide and also fed forward in a very even and uniform manner, and which is accomplished by the feed-rolls I I' and J J', both of which sets are provided with longitudinal flutes or grooves c and feeding ridges d. Both the grooves c and feeding-surfaces d of each feed-roll are formed diagonally or out of line with the axis of the roll, so that when the end d' of any given ridge or feeding-surface d next to the seam-guide is passing any given point in line with the axis of the feed-roll its other end, d', will be in rear or back of this line or point.

In Fig. 1 the diagonal grooves c and diagonal feeding ridges or surfaces d are shown, and it will be understood that the bottom feed-rolls, I I' and J J', are fluted or grooved diagonally to work in harmony with their respective upper feed-rolls—that is, the ends d' of the diagonal ridges or feeding-surfaces will always be in advance of their opposite ends, d"—and as the under feed-rolls, I I' and J J', turn up and to the left when acting upon the scrap of leather, M, to be split, they have to be made with reverse diagonal grooves or flutes c and reverse diagonal ridges or feeding-surfaces d to those in the upper feed-rolls, I I' and J J', which turn down and to the left, as indicated by arrows, Fig. 2, looking in the direction indicated by the arrow, Fig. 1.

I prefer to make the feed-rolls in shell form and then spline them to their respective journals, since they can be made more expeditiously in this way.

In brief, the ends d' of the diagonal ridges or feeding-surfaces d of both rolls in each set first come in contact with the surface of the scrap-leather M, and the remaining portions of the same diagonal ridges or feeding-surfaces gradually come in contact with the piece of scrap-leather, which is thus fed along by the combined screw action of the diagonal ridges

or feeding-surfaces *d* on both the upper and lower feed-roll, the action being such as to force the edge of the piece of leather up against the seam-guide *H*, while at the same time the 5 whole piece is fed along evenly and in a uniform manner to the splitting-knife, notwithstanding the pieces may vary greatly in thickness.

If preferred in any case, the machine may 10 be arranged so as to dispense with one set of feed-rolls, in which case the edging-knife, single set of feed-rolls, and splitting-knife would have to be relatively arranged to operate in harmony; but I prefer to use two sets, as herein 15 shown and described.

It will be further understood that in operating upon pieces of scrap-leather which have one even or straight edge the edging-knife and first set of feed-rolls may be dispensed with.

20 Having described my improvement in scrap-leather-splitting machines, what I claim as my invention, and desire to secure by Letters Patent, is—

1. The combination, with the seam-guide *H* 25 and edging-knife *C*, of the feed-rolls *I I'*, provided with diagonal grooves or flutes *c* and di-

agonal ridges or feeding surfaces *d*, as described, whereby the ends *d'* next to the seam-guide of the diagonal feeding ridges or surfaces *d* are always in advance of the opposite ends, *d''*, 30 substantially as and for the purposes set forth.

2. The combination, with the seam-guide *H* and splitting-knife *B*, of the feed-rolls *J J'*, provided with diagonal grooves or flutes *c* and diagonal ridges or feeding-surfaces *d*, as described, whereby the ends *d'* next to the seam-guide of the diagonal feeding ridges or surfaces *d* are always in advance of the opposite ends, *d''*, 35 substantially as and for the purposes set forth.

3. The combination, with the seam-guide *H*, 40 edging-knife *C*, and splitting-knife *B*, of the two sets of feed-rolls *I I'* and *J J'*, provided with diagonal grooves or flutes *c* and diagonal ridges or feeding surfaces *d*, as described, whereby the ends *d'* next to the seam-guide of the diagonal feeding ridges or surfaces *d* are always in advance of the opposite ends, *d''*, 45 substantially as and for the purposes set forth.

JOHN A. JOSSELYN.
